ATTORNEY

UNITED STATES PATENT OFFICE

HERMAN J. BAUMANN, OF WEST NEW YORK, NEW JERSEY

WINDOW SHADE ROLLER

Application filed December 5, 1930. Serial No. 500,173.

This invention relates to new and useful improvements in a shade drawer.

It is general construction to provide a shade drawer with a roller having a round end fixed on one end for engaging in a circular aperture in a wall bracket and a rectangular peg projecting from the other end connected with an internal spring within the roller and intended to engage a wall bracket having a rectangular opening so that the shade when drawn downwards winds the spring for automatically rewinding when so desired. It is also customary to form the wall bracket which has the rectangular opening with a slot so that the rectangular peg may be slipped into and out of the rectangular opening.

It is an object of this invention to so construct the shade roller that the rectangular peg upon the shade roller is depressible for eliminating the slot which communicates with the rectangular opening in the wall bracket so as to eliminate the possibility of the roller shade jumping out of the bracket when it is suddenly released.

Previous attempts have been made to form a shade roller with a depressible peg for the same purpose as the present invention, but these attempts have not met with commercial success due to various unsatisfactory mechanical structures.

It is an object of this invention to produce a shade roller of the class described which is of simple durable construction, dependable in use and efficient in action, and which can be manufactured and sold at a reasonable cost.

As a still further object of this invention it is proposed to provide a cap rigidly attached upon the end of the roller and supporting a cup carrying pawls engageable in longitudinal grooves formed in a circular portion of said rectangular peg, and to extend said peg through a spring rod seat and to attach said peg upon a spring rod provided with a coaxial spring attached at one end on the spring rod and at the other upon the rod seat whereby the spring tends to press the square peg outwards and allow its manual depression.

A still further object of this invention is to provide a means for normally holding the peg against depression and said means to be carried on said seat so that when the shade roller is accidentally released while in the drawn position, the shock cannot cause the depressible peg to accidentally become depressed upon the vibration whereupon the shade would fall from its supporting brackets.

A still further object of this invention is to provide a pivoted bell crank urged into an operative position by a spring with one of its ends acting against a portion of said square peg to accomplish the latching in the non-depressible condition.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is an elevational view of a roller shade constructed according to this invention and shown engaged in brackets upon a frame shown fragmentary and in section.

Fig. 2 is a transverse sectional view taken on the line 2—2 of Fig. 1.

Fig. 3 is a transverse sectional view taken on the line 3—3 of Fig. 1.

Fig. 4 is a fragmentary enlarged longitudinal sectional view taken on the line 4—4 of Fig. 1.

Fig. 5 is a transverse sectional view taken on the line 5—5 of Fig. 4.

Fig. 6 is a fragmentary longitudinal sectional view taken on the line 6—6 of Fig. 4.

Fig. 7 is a view similar to Fig. 6, but showing the rectangular peg depressed.

Fig. 8 is a perspective view of the spring rod seat.

The shade roller comprises a roller 10 with a hollow end 11, a round peg 12 on the solid end, a cap 13 on the hollow end, a cup 14 supported in the cap 13, pawls 15 on said cup, a rectangular peg 16 projecting from said cap 13 and having a portion 17

formed with longitudinal slots 18 for receiving said pawls 15, a spring rod seat 19 attached on said cup 14 and formed with an opening 20 through which a portion of said peg 16 passes, a spring rod 21 with one end engaging said seat 19 and attached on the end of said rectangular peg 16, and a spring 22 on said rod 21 and having one end attached on the rod and the other on said seat 19.

The roller 10 is shown of cylindrical form, and preferably should be made of wood. A cap 23 is shown upon the end of the roller 10 which is provided with the circular peg 12. A wall bracket 24 is shown attached upon a frame 25 and is formed with a circular aperture 26 for receiving the circular peg 12. Another wall bracket 27 is shown also attached upon a different portion of the frame 25 and is formed with a rectangular opening 28 for receiving the rectangular peg 16. It should be noticed that the wall bracket 27 has no slots communicating with the rectangular opening 28 so that it is necessary for the peg 16 to be depressible and extendable to engage within the opening.

The cap 13 is of tubular form and has its outer end turned inwards to form a marginal ring 29. The other end 30 of the cap is also turned inwards so as to engage into the material of the roller 10 and permanently attach these parts together. The cup 14 is formed with ring portion 31 of an external diameter corresponding with the internal diameter of the cap 13, and these parts are a forced fit so that they maintain relative positions. The pawls 15 are two in number and arranged diametrically opposite each other, and are pivotally mounted upon rivets 32 engaged through the cup 14.

The portion 17 of the peg 16 is of circular form and the longitudinal slots 18 are arranged diametrically opposite each other as clearly shown in Fig. 5. The pawls 15 are engageable in these slots so as to automatically hold the shade in the drawn position. The shade may be released as is customary by slightly drawing it downwards so that both pawls are in a disengaged position, and then releasing the shade so that centrifugal force holds the pawls spread and disengaged from the slots 18.

The spring rod seat 19 has a cup portion 33 into which the end of the spring rod 21 engages. The seat 19 also has a pair of diametrically opposite arms 34 extended at right angles against the cup 14 and having tongues 35 engageable through openings in the bottom of the cup and turned outwards to maintain the engaged positions. The rectangular peg 16 has a reduced end 36 which passes through the aperture 20 in the seat 19 and which is fixedly connected with the end of the rod 21.

The spring 22 is of the helical spiral type and is coaxially arranged upon the rod 21. One end of the rod is formed with a transverse slit 37 for receiving the end of the spring so as to hold these parts in relative position, and the other end of the spring is bent around one of the arms 34 of the rod seat 19. This arrangement allows the roller 10 to rotate relative to the stationary peg 16 and cause the spring 22 to become under tension for rewinding the roller upon release.

A means has also been provided for normally holding the peg 16 against being depressed, and said means being carried upon the seat 19. This means comprises a bell crank 38 pivotally mounted intermediately at 39 upon one of the arms 34 of the rod seat 19. One arm of the bell crank is urged against the rod seat 19 by a spring 40 which is attached upon the arm 34. In this position of the arm of the bell crank, it engages against the inner face of the portion 17 of the rectangular peg to restrain the peg from being depressed. The other end of the bell crank extends up through openings 41 in the roller 10 and in the cap 13 to the exterior of the device, where it terminates in a small handle portion 42. The bell crank 38 may be manually forced to the position shown in Fig. 7, and then the peg 16 may be depressed.

The operation of the device may be traced by assuming it in the condition shown in Fig. 1. A conventional shade may be attached upon the roller and used in a customary manner. Even though the shade is suddenly released and it winds up rapidly, it will not be capable of jumping out from the wall bracket as happens very often in present day outfits. In the first place the bracket 27 which accommodates one of the pegs of the shade roller has no lateral opening to allow disengagement. The only possible manner of disengagement is depression of the peg 16. Such depression is restrained by the outward urge of the spring 22. It is also made impossible by the bell crank 38. To remove the roller from the brackets, the bell crank must first be pivoted and then the peg depressed.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A shade roller, comprising a roller with a hollow end, a round peg on the solid end, a cap on the hollow end, a cup supported in the cap, pawls on said cup, a rec-

tangular peg projecting through said cap and having a portion with longitudinal slots for receiving said pawls, a spring rod seat attached on said cup and formed with an opening through which a portion of said peg passes, a spring rod with one end engaging said seat and attached on the inner end of said rectangular peg, and a spring on said rod having one end attached on said rod and the other on said seat whereby said peg is maintained resiliently extended by said spring.

2. A shade roller, comprising a roller with a hollow end, a round peg on the solid end, a cap on the hollow end, a cup supported in the cap, pawls on said cup, a rectangular peg projecting through said cap and having a portion with longitudinal slots for receiving said pawls, a spring rod seat attached on said cup and formed with an opening through which a portion of said peg passes, a spring rod with one end engaging said seat and attached on the inner end of said rectangular peg, and a spring on said rod having one end attached on said rod and the other on said seat whereby said peg is maintained resiliently extended by said spring, the portion of said rectangular peg which is provided with the longitudinal slots being of circular construction and extending through an opening in said cup.

3. A shade roller, comprising a roller with a hollow end, a round peg on the solid end, a cap on the hollow end, a cup supported in the cap, pawls on said cup, a rectangular peg projecting through said cap and having a portion with longitudinal slots for receiving said pawls, a spring rod seat attached on said cup and formed with an opening through which a portion of said peg passes, a spring rod with one end engaging said seat and attached on the inner end of said rectangular peg, and a spring on said rod having one end attached on said rod and the other on said seat whereby said peg is maintained resiliently extended by said spring, said rod seat having a cup portion for engaging the end of the rod, arm portions extending from said cup portion and directed against said cup, and means for attaching the arm portions onto the cup.

4. A shade roller, comprising a roller with a hollow end, a round peg on the solid end, a cap on the hollow end, a cup supported in the cap, pawls on said cup, a rectangular peg projecting through said cap and having a portion with longitudinal slots for receiving said pawls, a spring rod seat attached on said cup and formed with an opening through which a portion of said peg passes, a spring rod with one end engaging said seat and attached on the inner end of said rectangular peg, and a spring on said rod having one end attached on said rod and the

other on said seat whereby said peg is maintained resiliently extended by said spring, said rod seat having a cup portion for engaging the end of the rod, arm portions extending from said cup portion and directed against said cup, and means for attaching the arm portions into the cup, said latter means comprising tongues projecting from the arms and engaged through openings in the cup and turned at right angles after insertion.

5. A shade roller, comprising a roller with a hollow end, a round peg on the solid end, a cap on the hollow end, a cup supported in the cap, pawls on said cup, a rectangular peg projecting through said cap and having a portion with longitudinal slots for receiving said pawls, a spring rod seat attached on said cup and formed with an opening through which a portion of said peg passes, a spring rod with one end engaging said seat and attached on the inner end of said rectangular peg, and a spring on said rod having one end attached on said rod and the other on said seat whereby said peg is maintained resiliently extended by said spring, said spring rods being formed at its free end with a transverse slot receiving the end of the spring for relatively holding these parts, and the other end of the spring being connected upon an arm used for supporting said rod seat.

6. A shade roller, comprising a roller with a hollow end, a round peg on the solid end, a cap on the hollow end, a cup supported in the cap, pawls on said cup, a rectangular peg projecting through said cap and having a portion with longitudinal slots for receiving said pawls, a spring rod seat attached on said cup and formed with an opening through which a portion of said peg passes, a spring rod with one end engaging said seat and attached on the inner end of said rectangular peg, a spring on said rod having one end attached on said rod and the other on said seat whereby said peg is maintained resiliently extended by said spring, and means for normally holding said peg against depression and carried on said seat.

7. A shade roller, comprising a roller with a hollow end, a round peg on the solid end, a cap on the hollow end, a cup supported in the cap, pawls on said cup, a rectangular peg projecting from said cap and having a portion with longitudinal slots for receiving said pawls, a spring rod seat attached on said cup and formed with an opening through which a portion of said peg passes, a spring rod with one end engaging said seat and attached on the inner end of said rectangular peg, a spring on said rod having one end attached on said rod and the other on said seat, and means for normally holding said peg against depression and carried on said seat, comprising a bell crank pivotally

mounted intermediately on said seat, a spring urging one arm of said bell crank against said seat and behind a portion of the depressible peg to restrain depression, and the other end of said bell crank extending through openings in said roller and said cap to the exterior.

In testimony whereof I have affixed by signature.
